(57) **CLAIM**

The ornamental design for a translucent building block, as shown and described.

DESCRIPTION

FIG. 1 is a top plan view of a translucent building block showing my new design;

FIG. 2 is a bottom plan view thereof;

FIG. 3 is a front elevation view, it being understood the rear is a mirror image thereof;

FIG. 4 is a left elevation view, it being understood the right is a mirror image thereof;

FIG. 5 is an enlarged lower right axonometric view thereof;

FIG. 6 is an enlarged lower left axonometric view thereof;

FIG. 7 is a top plan view of a translucent building block shown on a reduced scale with a multiplicity of like blocks creating a wall thereof; and,

FIG. 8 is an axonometric view of a translucent building block shown on a reduced scale with a multiplicity of like blocks creating a wall thereof.
